UNITED STATES PATENT OFFICE.

ABRAHAM NOVICK, OF FLUSHING, NEW YORK, ASSIGNOR TO F. L. SMITH'S MACHINE COMPANY, INCORPORATED, OF NEW YORK, N. Y., A CORPORATION OF NEW YORK.

SHEET-FOLDING MECHANISM FOR ENVELOPES AND THE LIKE.

Application filed November 6, 1923. Serial No. 673,049.

This invention relates to mechanism for folding paper or like sheet material for the purpose of forming articles such as envelopes.

5 The general object of the invention is to provide a new and improved mechanism whereby the folding operation may be performed with accuracy and speed while the blank is passing through the machine.

The invention is herein shown and described as embodied in an envelope making machine and serving to fold the bottom flaps of the envelopes made by such machine.

The characteristic novel features of the invention will be hereinafter pointed out in the description of the mechanism illustrated and in the appended claims.

The invention will be understood from the following description, taken in connection with the accompanying drawings, in which Figure 1 is an elevation of a portion of an envelope making machine having the invention embodied therein; Figure 2 is a partial section of Figure 3 taken on line II—II, looking in the direction of the arrow, to show particularly the means for supporting the folding blades; Figure 3 is a fragmentary side elevation, partly a section, of certain of the parts shown in Figures 1 and 2; and Figures 4 and 5 are fragmentary side elevations, partly in section, showing the elements of the bottom flap folding mechanism in various operative positions.

Referring to the drawings, and particularly to Figure 1, portions of the frame of an envelope making machine are represented by the parts 8 and 9. Between the frame members 8 and 9, and inclined to the vertical, are forming blades 12 and 13 which cooperate with the blank to be folded. The means by which the blanks are fed downwardly behind the forming blades 12 and 13, forms no part of the present invention and need not be further described than to say that in its essential elements it comprises a feed belt 15 the lower reach of which is supported upon the pulley 16, the front surface of this belt being in substantially the same plane as the back surfaces of the folding blades 12 and 13 and the front surfaces of the fixed guides 18 and 19. Frictional engagement between the envelope blanks and the belt 15 is increased by rollers 21 (Fig. 2) yieldingly pressed towards the belt 15 in a manner which it is unnecessary to il-

lustrate. Figure 2 shows the manner in which the parts just mentioned cooperate with an envelope blank, the latter being indicated by a dot-and-dash line. In Figure 1, an envelope blank is shown in dash lines before folding, and is shown in dot-and-dash lines after the side flaps have been folded over the forming blades 12 and 13, it being understood that this folding operation is accomplished by means which are not illustrated since they form no part of the present invention. The lower flap of the envelope is shown in Figure 1 as cooperating with the bottom folding mechanism and stops thereon which will be hereinafter described.

The manner in which the forming blades 12 and 13 are supported and actuated will now be described. These blades, for the purpose of feeding the blanks to the bottom folding and drawing off mechanism, herein-after described, are reciprocated longitudinally; and in order to permit high speed operation the weight of the parts which are thus moved is reduced to a minimum. Provision is also made for adjustment of the forming blades 12 and 13 laterally, so as to adapt them for engagement with envelope blanks of different sizes. As shown in Figures 2 and 3, each of the forming blades 12 and 13 is secured to an end of a bracket 23, the other end of which is attached to a slide 25 adapted to move in a slide-way 27. Each of the slide-ways 27 has projecting from it, at substantially a right angle, a portion 29 forming another slide-way adapted to cooperate with a cross frame member 30. Each of the slide ways 27 is shown as provided upon each side of its channel with a cover plate 32 which overlaps the edge of the slide 25; and on its other side said slide-way has an opening adapted to receive the lugs 34 extending forwardly from the slide 25. The slideway 29 is shown as provided with a cover plate 36 secured in place by screws 37 (Fig. 2) and with set screws 38, the latter serving to hold the slide-ways 29 at any desired locations on the cross frame 30. The slide 25, carrying the brackets 23 which in turn carry the forming blades 12 and 13, are reciprocated in the slide-ways 27 by a system of levers actuated from a cam 40 (Fig. 3) which is mounted upon and secured to a constantly driven shaft 42 journaled in the frames 8 and 9. The cam 40 is engaged by a cam roller 44 rotatably

mounted on a lug which extends from the side of a lever 46. The lower end of lever 46 is pivotally mounted on a stud 48 projecting from the frame member 9; and pivotally connected to the upper end of lever 46 is a connecting rod 50 which at its other end is pivotally secured to the end of a lever 52 attached to a shaft 54 journaled in the frame members 8 and 9. As shown in Figure 3, the end of the lever 52 is provided with a slot in which at any desired location may be secured the pin to which the end of the connecting rod 50 is pivotally connected, thereby providing for the adjustment of the effective length of the lever 52 and of the length of stroke of the forming blades. Mounted upon and secured to the shaft 54 are levers 56 to the end of each of which is secured a pin 58 which rotatably and slidably engages a hole in a block 60 arranged for sliding movement between the lugs 34 extending forwardly from each of the slides 25. With this construction, it will be apparent that as the cam 40 rotates, the shaft 54 will be rotatably reciprocated through the medium of the cam roller 44, lever 46, connecting rod 50, and lever 52; and that the slides 25, carrying the brackets 23 to which are secured the forming blades 12 and 13, will be reciprocated in unison owing to the angular movement of the levers 56 and the pivotal connections between the ends of those levers and the slides 25. Owing to the fact that the locations of the parts including the slide-ways 27 may be adjusted laterally of the machine upon the cross frame member 30 when the set screws 38 are loosened and that the blocks 60 slide upon the pins 58, it will be seen that the position of the forming blades 12 and 13 with reference to the belt 15 may be easily adjusted for different sizes of envelope blanks to be folded.

It will of course be understood that the shaft 42 is so geared that the forming blades 12 and 13 in their reciprocating movement will properly cooperate with the other elements of the machine, and particularly with the bottom flap folding and drawing off mechanism which will now be described.

The mechanism shown located below the ends of the forming blades 12 and 13 has three functions, namely, the limiting of the downward movement of the blank prior to the folding operations, the folding of the bottom flap of the envelope and the drawing off of the envelope from the forming blades 12 and 13. Figures 1 and 3 show the mechanism about to be described in position to perform these functions. As shown in these figures, the envelope blank in its downward movement, before the side folding operations take place, comes to rest with its bottom flap extending over the bottom flap folding plate 68 and with the apexes of the obtuse angles

between the bottom flap and the side flaps of the blank in engagement with stops carried by the flap folding mechanism. These stops consist of sliding members 65 having upturned ends 66 which are engaged by the edges of the blank; and these sliding members are adjustably secured to a bar 67 carrying the flap folding plate 68, by means of screws or bolts 69 which extend through the slots and into the bar 67. With this construction, it will be obvious that the stops 65 may be adjusted so that the inner faces of the upturned ends 66 will lie approximately in line with the outer edges of the forming blades 12 and 13 in whatever position said blades may be set; thereby adapting the stops to engagement with envelope blanks of different sizes. The bar 67 is provided at its ends with brackets 70 having holes therein adapted to receive a rod 72 set screws 73 being provided for adjustably controlling the angular position of said brackets with reference to said rod. The rod 72 is fixed in the ends of levers 74 which are secured to and extend from a shaft 75 suitably journaled in the frame of the machine or in brackets 76 extending therefrom. Rotatably mounted on the shaft 75 is an arm 77 carrying at its end a cam follower in the form of a roller 78 which cooperates with the cam 79 fixed upon a constantly rotating shaft 80 journaled in the machine frame. The hub of the arm 77 is provided with a cutaway portion 81 as shown, thru which projects a pin 82 secured in and extending radially from the shaft 75. Secured to the outer end of the pin 82 and to a point on the arm 77 is a spring 83 which serves to yieldingly hold the arm 77 in such a position with reference to the shaft 75 that the pin 82 is in engagement with an adjustable stop in the form of a screw 84 mounted in a lug extending from one side of the arm 77. A spring 85, attached at one end to the lever 77 and at the other end to some fixed part, serves to hold the roller 78 in engagement with the surface of the cam 79. It will thus be apparent that the cam 79 during its rotation normally causes the bar 67 and the flap folding plate 68 carried by it, to assume and remain for certain periods of time in either the position shown in Figure 3 or the position shown in Figures 4 and 5. If, however, the envelope blank for any reason becomes jammed so as to interfere with the movement of the folding plate 68, injury to or breakage of the bottom flap folding mechanism will be prevented, because the movement of the folding plate 68 in one direction is caused merely by the spring 85 acting upon the arm 77, and in the other direction is due to the pull of the spring 83 as the arm 77 is moved under the influence of the cam 79. Thus, if the folding plate 68 by the jamming of the envelope blank is

held in the position shown in Figure 4, the arm 77 will be rocked as usual by the cam 79, but the yielding of the spring 83 will allow the shaft 75 and the lever 74 mounted thereon to remain stationary; and if the folding plate 68 is held in the position shown in Figure 3, the result will be merely that the spring 85 will fail to move the arm 77 so as to cause the roller 78 to follow the cam 79 throughout its smaller diameter.

It will be understood, of course, that the relative speeds of the shafts 42 and 80, and the forms of the cams 40 and 79, are such that the movement of the bottom flap folding plate 68 from the position shown in Figure 3 to the positions shown in Figures 4 and 5 will take place just before the forming blades 12 and 13 are projected downwardly; and that the return movement of the bottom flap folding plate will take place just after the lower ends of the forming blades have been withdrawn upwardly out of the path of said flap folding plate. As will be obvious from Figures 4 and 5, the bottom flap of the envelope blank is bent upwardly by the forward movement of the bar 67 and the flap folding plate 68; and that, as the forming blades 12 and 13 move downwardly the bottom flap of the envelope is slidingly engaged by the rear side of the flap folding plate 64. Near the end of this downward movement of the forming blades 12 and 13 and the folded envelope blank carried thereby, the lower folded edge of the envelope is thrust by the forming blades into engagement with certain cooperating drawing-off rollers 86 and 87 which seize the envelope and strip it from the forming blades 12 and 13. The drawing-off roller 86 is mounted upon a constantly driven shaft 89 suitably journaled in the machine frames; and the roller 87 is secured to a shaft 90 which is rotatably mounted in movable bearings 91 with which cooperate springs 92 serving to yieldingly hold said bearings in such positions that the roller 87 acts as an idler to hold the envelopes in frictional engagement with the roller 86. As shown in Figure 1, the flap folding plate 68 is preferably notched at its bottom edge so that the bottom fold of the envelope will be engaged, on its outside by said folding plate 68 and on the inside by the forming plates 12 and 13, until the envelope has been gripped between the rollers 86 and 87. In this manner, the proper drawing off of the envelope from the forming blades is assured.

Variations may be resorted to without departing from the scope of my invention.

60 What I claim is:

1. In combination, means for supporting a blank to be folded, forming blade means having an edge about which the blank is to be folded, folding means cooperating with said forming blade means to fold the blank

against the said edge and stops carried by said folding means for controlling the position of said blank.

2. In combination, means for supporting a blank to be folded, forming blade means having an edge about which the blank is to be folded, folding means cooperating with said forming blade means to fold the blank about the said edge, and adjustable stops carried by said folding means for controlling the position of said blank.

3. In combination, means for supporting a blank to be folded, adjustably supported forming blades having an edge about which the blank is to be folded, folding means cooperating with the ends of said forming blades to fold the blank about the said edge, and stops adjustably mounted on said folding means and adapted to cooperate with said blank and support the same in proper position with reference to said forming blades and folding means.

4. In combination, means for supporting a blank to be folded, folding means, forming blades having an edge about which the blank is to be folded, means for supporting said forming blades so as to permit longitudinal movement thereof, means upon which said blade supporting means are adjustably mounted to permit lateral adjustment thereof, and operating mechanism for periodically reciprocating said forming blades.

5. In combination, means for supporting the blank to be folded, folding means, forming blades having an edge about which the blank is to be folded, brackets secured to said forming blades, means for supporting said brackets, means upon which said bracket supporting means are adjustably mounted, and an operating mechanism for periodically reciprocating said forming blades.

6. In combination, means for supporting the blank to be folded, folding means, forming blades lying in the same plane and parallel to one another, separate means for supporting each forming blade so as to permit longitudinal movement thereof, a common means upon which each of said blade supporting means is adjustably mounted, a shaft which is periodically partially rotated in opposite directions, and connecting means between said shaft and each blade supporting means whereby the latter are periodically reciprocated.

7. In a folding mechanism, forming means, a movably supported folding blade, means for yieldingly moving said blade in a direction to fold a blank, and means for yieldingly moving the blade in the opposite direction to return it to initial position.

8. In a folding mechanism, forming means, a movably supported folding blade, an actuating member cooperative with said blade, means for moving said actuating member positively in one direction and yieldingly in

the opposite direction, and yielding means interposed between said actuating member and said folding blade for causing the blade to be yieldingly moved in response to the 5 positive movement of the actuating member.

9. In a folding mechanism, forming blades, means cooperating with the forming blades to position a blank in a definite plane for folding, a folding blade initially at 10 the opposite side of the blank plane from the forming blades, means for moving the folding blade transversely of the blank plane to turn the blank around the forming blades, and means for moving the forming 15 blades along the folding blade to crease the fold and feed the blank.

10. In a folding mechanism, forming blades, means cooperating with the forming blades to position a blank in a definite plane 20 for folding, a folding blade initially at the

opposite side of the blank plane from the forming blades, means for moving the folding blade transversely of the blank plane to turn the blank around the forming blades, means for moving the forming blades along 25 the folding blade to crease the fold and to advance the blank, and mechanism for taking the folded and advanced blank off the forming blades and further advancing it.

11. In a folding mechanism forming 30 blades, means cooperating with the forming blades to position a blank against the rear of the forming blades, a folding blade movable from rear to front of the forming blades to turn the blank around the forming 35 blades, and means for moving the forming blades along the rear of the folding blade, in the plane of the blank and transversely of said fold, to crease the fold.

ABRAHAM NOVICK.

CERTIFICATE OF CORRECTION.

Patent No. 1,616,982,

granted February 8, 1927.

to ABRAHAM NOVICK.

It is hereby certified that error appears in the printed specification of the above mentioned patent requiring correction as follows: Page 3, line 66, claim 1, for the word "against" read "about"; and that the said Letters Patent should be read with this correction therein that the same may conform to the record of the case in the Patent Office.

Signed and sealed this 1st day of March, A. D. 1927.
